EMIL WEITZEL, OF PHILADELPHIA, PENNSYLVANIA.

CLAMPING DEVICE FOR TYPE.

1,208,867.

Specification of Letters Patent. Patented Dec. 19, 1916.

Application filed April 24, 1916. Serial No. 93,281.

To all whom it may concern:

Be it known that I, EMIL WEITZEL, a citizen of the United States, residing at Philadelphia, in the county of Philadelphia and State of Pennsylvania, have invented a new and useful Clamping Device for Type, of which the following is a specification.

This invention has reference to clamping devices for type, and its object is to provide a device to take the place of ordinary tie-ups.

In accordance with the present invention each device comprises two side bars and two end bars, which latter constitute clamps, the device inclosing the type and clamping them firmly in the same manner and with better effect than is customarily accomplished by tying the make-up together with a string.

The device admits of better proofs, quicker handling, and considerable time saved for general make-up. Each page of make-up is provided with a plate on which it rests. Since the usual custom of tying up and untying the pages of the make-up takes considerable time, the present invention facilitates the making of alterations and the run over of lines. Better alinement of lines is obtained, and the pages incased by the device are ready for the imposing stone or lay out on the stone. All the stoneman has to do is to take out the clamps and side bars and lock up the form. Moreover, the inclosing device and plates permit the gaining of considerable space for storing pages.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:—Figure 1 is a plan view of a make-up in which the present invention is utilized. Fig. 2 is a longitudinal section thereof. Fig. 3 is a perspective view of the clamp frame. Fig. 4 is a section on the line 4—4 of Fig. 3.

Referring to the drawings, there are shown two side bars 1 and 2 which may be alike. There are also shown two clamp bars 3 and 4 which may also be alike. Each side

bar is formed near one end with a notch or recess 5 extending into one edge of the bar perpendicular to the length of the latter for about half the width of the bar, although any particular distance is not obligatory. The other end of the bar has a series of notches 6 similar to the notch 5, and these notches are spaced from the first-named notch and are also spaced apart to accommodate octavo, quarto and larger pages. The end bars, which may be termed clamp bars, each have near one end a notch 7 entering one edge perpendicular to the length of the bar and designed to match the notch 5, so that each clamp bar may be joined to a respective side bar which in the particular instance shown is the bar 2, so that the clamp bar extends perpendicular to the side bar with the upper edges of the side bars and clamp bars in one plane.

The other end of each end or clamp bar 3 and 4 has a series of notches 8 generally similar to the notch 7 and designed in the case of the end or clamp bar 3 to engage the notch 5 of the bar 1, and in the case of the bar 4 to engage in one of the notches 6 of the bar 1; that is, a notch 8 will embrace a bar 1 on opposite faces thereof, with the notch 5 or 6, as the case may be, embracing the bar 3 or 4, as the case may be. There is thereby formed a rectangular frame variable in width because of the presence of the notches 8 and variable in length because of the presence of the notches 6. Each notch 7 on the side thereof toward the adjacent end of the bar 3 or 4 is slightly curved or beveled outwardly, as indicated at 9, and each notch 8 has the edge toward the opposite end of the bar 3 or 4 curved or beveled outwardly, as indicated at 10. Each of the bars 3 and 4 at its outer end is provided with other notches 11, which, when the parts are assembled, are exterior to the frame thus formed and provide convenient means for the handling of the bars 3 and 4.

With the bars 1, 2, 3 and 4 there may be formed a rectangular frame of somewhat less than type height and of an interior area to inclose and clamp a standard size body of type representing a certain standard page. The notches 7 and 8 are so arranged as to provide for different widths of page and the notches 5 and 6 are so arranged as to provide for different lengths of page. When the frame thus formed is about a body of type the interior dimensions of the frame

are such as to snugly hold the type, the curved sides 9 and 10 of the notches 7 and 8, respectively, acting to draw the bars 1 and 2 toward each other into tightly clamping relation to the type inclosed by the frame. Then the type is tightly bound in place to better advantage than is the case where the type are tied together with a piece of cord.

10 For each page of type there is provided a plate 12 with an upstanding flange 13 at one edge and an upstanding flange 14 at one end, while the edges of the plate not provided with flanges are beveled, as shown 15 at 15 and 16, respectively, although it will be understood that but one of the edges need be beveled. The plate 12 provides for the type when not on the stone, but the body of type is readily slid off of the plate because of the presence of the beveled edge or 20 edges. In the drawings the type are conventionally indicated at 17.

The side bars are smooth or plane on both the inside and outside faces, so that they 25 can be used both ways. The notch 5 of each side bar is located at that end which is customarily the top end of the clamp, that is, the end toward the top of the page of type. The notches 11 permit ready opening of the 30 whole lock for correction or run over of lines, while the remaining notches provide for variations in size of pages. The curvature 9 and 10 is of particular importance because serving to bind the side bars tightly 35 against the type inclosed in the frame or lock.

One set of side bars and end or clamp bars will provide for various size pages, so that 40 a printer has only to obtain a sufficient number of these bars to accommodate all the pages he will need to have locked up in them and the bars may all be of the same size, since they provide for differences in page size.

With the invention the time heretofore 45 lost in tying up the pages with cord is avoided, better proofs are obtained than before, there are no "off their feet" complaints, and the pages are always readily corrected when needed. 50

What is claimed is:—

1. A clamping device for type, comprising two side bars each with a single notch in one edge near one end and arranged perpendicular to the length of the bar and a series of notches in the same edge and located near the other end of and also perpendicular to the length of the bar, and two end bars each with a single notch in one edge near one end and perpendicular to the 55 length of the bar and a series of like notches in the same edge near the other end, with the notches of one bar adapted to receive a corresponding portion of the other bar. 60

2. A clamping device for type, comprising two side bars each with a single notch in one edge near one end and arranged perpendicular to the length of the bar and a series of notches in the same edge and located near 70 the other end of and also perpendicular to the length of the bar, and two end bars each with a single notch in one edge near one end and perpendicular to the length of the bar and a series of like notches in the same edge 75 near the other end, with the notches of one bar adapted to receive a corresponding portion of the other bar, and each end bar having a notch in the end edge for permitting the lifting of the bar from engagement with 80 the side bars.

In testimony, that I claim the foregoing as my own, I have hereto affixed my signature in the presence of two witnesses.

EMIL WEITZEL.
